Amos B. Bergman, Inventor,
By his Attorney,
Raymond & Blakeslee.

UNITED STATES PATENT OFFICE.

AMOS C. BERGMAN, OF NEW YORK, N. Y.

PRACTICE-CLAVIER.

SPECIFICATION forming part of Letters Patent No. 689,779, dated December 24, 1901.

Application filed January 31, 1901. Serial No. 45,530. (No model.)

To all whom it may concern:

Be it known that I, AMOS C. BERGMAN, a citizen of the United States, residing at New York, in the county of New York and State 5 of New York, have invented certain new and useful Improvements in Practice-Claviers, of which the following is a specification.

This invention relates to practice-claviers; and it has for its object to provide means 10 whereby the volume and quality of sound which is caused by the sound-producing or "click" devices which are customarily embodied in practice-claviers may be enhanced.

The present invention constitutes an improvement or addition with respect to subject-matter embodied in prior applications for Letters Patent filed by me, respectively, June 5, 1900, and November 14, 1900, and respectively bearing the Serial Nos. 19,123 and 20 36,463.

In carrying out my present invention I employ a vibration conductor or bridge, whereby the sound-producing or click device is positively connected with the base, frame, or 25 casing of the action of the practice-clavier, which is thus thrown into operative vibratory association with the sound-producing or click device, whereby the total vibratory effect of the impact of the striker devices upon the 30 sound-producing or click device is altered in quality and increased in quantity, the resultant sound or click being relatively deeper, clearer, and more positive.

In the drawings, Figure 1 is a longitudinal 35 sectional view of a practice-clavier embodying my present invention, several of the parts being broken away for clearness of illustration. Fig. 2 is a detail or fragmentary plan view of the construction illustrated in Fig. 1.

Corresponding parts in both figures are denoted by the same reference characters.

Referring to the drawings, 1 designates the casing of a practice-clavier, which embodies in its box-like formation a top member 2, side 45 members 3, a rear member 4, and a bottom member 5. The casing 1 may be of any preferred and suitable form, according to the structural conditions obtaining. Within the casing are arranged the keys 6 and the sound-producing devices or elements, two of which are preferably employed, as illustrated at 7

and 8. In the preferred form of construction, as disclosed in the prior applications initially herein referred to, the sound-producing elements 7 and 8 are operated upon by a plurality of hammer elements, one for and operated by each key, as illustrated at 9. Each hammer element embodies a separate striker device 10, arranged and adapted for operative contact with each of the sound-producing elements 7 and 8 under actuation of the respective key 6. The hammer elements and striker devices carried thereby are operated by the keys in a vertical path of movement, the hammer elements being each pivotally supported at one end, as at 11. The sound-producing elements 7 and 8 are capable of vertical adjustment through the agency of suitable adjusting means, as at 12 and 13, respectively, into and out of the paths of play 70 of the striker devices 10.

It will be noted that in the preferred arrangement and method of adjustment of the sound-producing devices with respect to the paths of play of the striker devices the sound-producing devices have no positive vibration-transmitting connection with any vibratory element or device, such as the casing 1, and the sound which results when the sound-producing devices are operatively engaged or 80 struck by the striker devices is consequently "thin" or lacking in body, weak, and high in "pitch," qualities which render the said resultant sound lacking in the positive audible or acoustic properties or qualities which 85 are essential in the art under consideration.

In the practice of my present invention, which provides means for overcoming the above demerits or negative qualities, I provide a vibration conductor or bridge A, which 90 is positively connected with the casing 1 and preferably with the rear member 4 of the same, as at 14, and is arranged to bear positively with its free end portion a upon the sound-producing element 7, as illustrated. A similar vibration conductor or bridge may be similarly arranged for operation with respect to the sound-producing element 8, as will be manifest, although the same is not illustrated in the drawings. Suitable tensional means 15 or tensional means 16, or both, may be provided to enhance the positive bearing of the 100

vibration conductor or bridge A upon the sound-producing element.

In the preferred form of construction the conductor or bridge A consists of a relatively broad and thick body-strip 17, of wood or other suitable material, which is pivotally connected with the casing member 4 by means of a hinge 18 and is slightly reversely curved in its opposite end portions, as at 19 and 20, respectively, whereby it arches upwardly at its end portion adjacent the casing member 4 and arches downwardly at its end portion with which it engages with the sound-producing element. This reversely-curved formation secures a braced relation between the casing and the sound-producing element, whereby the transmission of vibration from the latter to the former is effectively enhanced. The end portion a of the conductor or bridge A, which end portion contacts with the sound-producing element, is curved in its lower or operative surface portion, as at 21, and padded, as at 22, with a covering of felt or other yielding substance, which insures an intimate co- engagement of parts. By means of the hinge connection 18 the conductor or bridge A is free to follow the sound-producing element 7 in its vertical movement of adjustment.

The tensional means 15 consists of a leaf or plate spring 23, which is connected at one end, as at 24, with the casing 1 at a point adjacent the point of connection 14 of the conductor or bridge A and the casing and is curved longitudinally, whereby it bears positively upon the conductor or bridge A, preferably intermediately of its oppositely-curved end portions 19 and 20, as at 25.

The tensional means 16 consists of a coiled spring 26, which is connected at one end, as at 27, with the conductor or bridge A and at the other end at a suitable point, as at 28, preferably with the support 11 of the hammer element 9.

In the preferred form of construction the tensional means 15 and 16 exert their tendencies at opposite sides or points of the conductor or bridge A, and either one or both of the same may be employed at the same time, as desired.

50 It is manifest that any desired number of the conductors or bridges A may be provided for either or both of the sound-producing elements, according to the requirements to be met.

55 The operation and advantages of my improved means for enhancing the volume and quality of sound of sound-producing elements in practice-claviers will be readily understood by those skilled in the art to which it appertains. The vibration conductor or bridge A is maintained firmly in contact with the sound-producing element by the tensional means 15 or 16, or both, and follows the sound-producing element in operative contact in all the phases of adjustment of the latter. By means of the conductor or bridge

A the casing 1 of the practice-clavier action is maintained in sympathetic vibratory relation with the sound-producing element, materially and effectively enhancing the sound produced by the engagement of the striker devices with the same. The specific reversely-curved formation of the body-strip 17 of the conductor or bridge A is advantageous with respect to firmness of operative connection of the casing with the sound-producing element and perfect vibration transmission or conduction. The curved lower surface formation of the contact end portion of the conductor or bridge A enables perfect contact of the parts at all phases of adjustment of the sound-producing element.

I do not desire to be understood as limiting myself to the specific features of formation, proportion, arrangement, and association of parts as herein described and illustrated, but reserve the right to all such modifications and variations of the same as shall fall within the scope of my invention and the terms of the following claims.

Having thus described my invention, I claim and desire to secure by Letters Patent—

1. In a practice-clavier, a movable sound-producing element, an independent vibratory element, and a vibration conductor or bridge which operates in connection with the sound-producing element and the independent vibratory element, said vibration conductor or bridge being permanently and movably connected with one of said elements and arranged for operative contact with the other of said elements.

2. In a practice-clavier, a movable sound-producing element, an independent vibratory element, a vibration conductor or bridge which operates in connection with the sound-producing element and the independent vibratory element, said vibration conductor or bridge being permanently and movably connected with one of said elements and arranged for operative contact with the other of said elements, and means for maintaining the vibration conductor or bridge in positive operative contact with the sound-producing element.

3. In a practice-clavier, a movable sound-producing element, an independent vibratory element, a vibration conductor or bridge permanently pivoted to the independent vibratory element, and means for maintaining the vibration conductor or bridge in positive operative contact with the sound-producing element.

4. In a practice-clavier, a casing, an adjustable sound-producing element arranged therein, a vibration conductor or bridge permanently pivoted to the casing and arranged for oscillation in the path of adjustment of the sound-producing element, and tensional means for normally maintaining said vibration conductor or bridge in positive operative

contact with said sound-producing element whereby the sound-producing element and the casing are united in vibratory relation.

5. In a practice-clavier, a sound-producing element, an independent vibratory element, and a vibration conductor or bridge permanently connected with the latter and arranged for operative contact with the former, said vibration conductor or bridge consisting of
10 a body-strip which is reversely curved at its opposite ends one of which is connected with

the independent vibratory element and the other of which ends is adapted for engagement with the sound-producing element.

In testimony whereof I have signed my ¹⁵ name, in the presence of the subscribing witnesses, this 22d day of November, 1900.

AMOS C. BERGMAN.
